UNITED STATES PATENT OFFICE.

JOSEF HOELLER, OF ALBIA, IOWA.

PENCIL-SHARPENER.

1,266,806.

Specification of Letters Patent. Patented May 21, 1918.

Application filed April 22, 1916. Serial No. 92,918.

To all whom it may concern:

Be it known that I, JOSEF HOELLER, citizen of the United States, residing at Albia, in the county of Monroe and State of Iowa, have invented certain new and useful Improvements in Pencil-Sharpener, of which the following is a specification.

It is an object of this invention to provide a pencil sharpener adapted to be removably engaged with one end of the lead pencil so as to be immediately available for use in the event the pencil point becomes broken, and which embodies certain other useful and novel features of construction.

In the drawings:

Figure 1 is a perspective view of a pencil showing my device applied to one end thereof.

Fig. 2 is a vertical section of the device showing the device applied to the pencil, the pencil being shown in elevation.

Fig. 3 is a sectional view upon the line 3—3 of Fig. 2.

The numeral 1 indicates a cylindrical body portion having a conical bore 2 for the reception of the end of a pencil. A slot 3 is cut in the cylindrical body communicating with the conical bore. As will be seen upon inspection of the drawings the metal 30 of the body portion 1 is cut away at one side of the slot 3, as at 4, to provide a cutting edge 5. By referring to Fig. 3 it will be seen that the conical inner wall is slightly hollowed out, as at 6, to obtain the desired angle of the cutting edge 5 with relation to the pencil to be sharpened. A socket 7 is formed in the upper end of the cylindrical body and is adapted to receive an eraser 8. The opposite or lower end of the cylindrical 40 body is interiorly threaded, as at 9, for engagement with the threaded end of a tubular clip 10, the said clip being split a portion of its length upon either side thereof to provide for engagement with pencils of varying diameters. A ring 11 is adapted to be slipped down over the split portion of the clip to hold the same tightly in engagement with the pencil, the said ring being provided with a spring catch 12 for en-

50 gaging the edge of a pocket.

In use this sharpener is placed upon the broken end of the pencil and the pencil is rotated therein in the manner usually employed in using a device of this character. It will be noted in connection with this device that a pencil may be sharpened at both ends and my device engaged with one end thereof whereby when the opposite end becomes broken while in use the device may be removed from the sharpened end and placed on the broken end which may be then sharpened at the leisure of the writer. To take the place of the usual eraser which is carried by the end of the pencil an eraser has been disposed in the end of said sharpener. It will be also noted that by means of the construction of the clip 10 that the same may be held tightly in engagement with pencils of various sizes, and that by means of a catch 12 the pencil may be retained against loss in a pocket.

While, it will be seen from the description taken in connection with the drawings, that I have provided a device clearly efficient and operable for the purpose described, I do not claim the exact construction shown therein, but reserve the right to make certain minor changes and alterations as will not depart from the spirit and scope of the appended claim.

I claim:

A pencil sharpener, comprising a solid body of cylindrical form having an axial conical bore, and having a longitudinal slot in a side terminating a distance from each end of the body, said slot being radial and leading into the conical bore and having a wall cut away to provide a cutting edge, the wall of the conical bore having a portion adjacent the longitudinal slot hollowed out to give prominence to the cutting edge.

In testimony whereof I affix my signature in presence of two witnesses.

JOSEF HOELLER.
